UNITED STATES PATENT OFFICE.

DANIEL W. MARMON, OF INDIANAPOLIS, INDIANA, ASSIGNOR TO THE
NORDYKE & MARMON COMPANY, OF SAME PLACE.

AUTOMATIC FEED-GATE.

SPECIFICATION forming part of Letters Patent No. 281,707, dated July 24, 1883.

Application filed December 26, 1882. (No model.)

To all whom it may concern:

Be it known that I, DANIEL W. MARMON, of the city of Indianapolis, county of Marion, and State of Indiana, have invented certain new and useful Improvements in Automatic Feed-Gates, of which the following is a specification.

My invention relates to that class of feeding devices which are adapted to be automatically operated by the material passing through them, or, in other words, in which the opening is increased by the additional weight of the material as the hopper fills, and decreased as the amount of material in the hopper grows less. It is especially intended to be used with roller-mills, but may be used with middlings-purifiers, or in any place where fine material is to be gradually fed to a machine.

Referring to the accompanying drawings, which are made a part hereof, and on which similar letters of reference indicate similar parts, Figure 1 is a transverse vertical section on the dotted line *z z*, Fig. 2, of the hopper and feed mechanism of a roller-mill embodying my improved gate; Fig. 2, a side elevation of the same; and Fig. 3, a horizontal sectional view, looking upwardly from the dotted line *y y*, Fig. 2, showing the gate and feed-rolls in under-side plan.

In said drawings, the portions marked *A* represent my improved gate, *B* the feed-roll, and *C* the hopper, said hopper and feed-roll being of any desired or appropriate forms. The gate *A* extends from end to end of the machine, alongside the feed-roll, and is mounted on pivots *a*, near the feed-exit of the hopper. It has an arm, *A'*, which extends around to a point inside the hopper, above the roll, upon which is a lug, *a'*, to which a spring, *A²*, is attached. The effect of this spring, as will be readily seen, is to urge the gate toward or against the roll *B*. A small rod, *a²*, at the end of this spring, and a thumb-nut thereon, or some other suitable means of adjustment, should be employed to regulate the tension of this spring, and thus determine the force necessary to overcome it to increase the feed. The spring is secured to the hopper by a suitable eye or clip, *c*. A suitable weight might be used instead of the spring *A²*, if desired,

though I prefer the spring, as being more sensitive than a weight. Attached to or resting against the inner end of the arm *A'* is a pressure-board, *A³*. The preferable (because simpler) construction is that shown at the right of Fig. 1, where the board is shown attached rigidly to the arm *A'*; but pivoting the board separately on a pivot, *a³*, accomplishes the same result. The board *A³* is surrounded with flexible material *a⁴*, (as cloth,) which is also attached to the hopper, and prevents any of the material from getting behind the pressure-board.

The operation of my invention is as follows: The spring *A²*, when the hopper is empty, closes the gate *A*. As the hopper *C* is filled, as soon as the grain or other material reaches the pressure-board it begins to press it back, opening the gate and allowing the material to escape. As the material rises it exerts an increased pressure upon the board until the gate is opened to such an extent as to discharge an equal amount to that delivered to the hopper, or to its full capacity. In case the delivery of material to the hopper should be checked, the decreased pressure permits the spring *A²* to close the gate sufficiently to maintain an equality between the inflow and outflow of the material. In case the inflow should cease, the gate would close, but would immediately reopen upon the supply being resumed.

A distinguishing feature of my invention is that the force of the material in the hopper increases more than proportionally as said material rises nearer the top of the hopper. The reason for this is that the pressure-board is pivoted near to or below its lower edge, and the material therefore has a leverage which increases, of course, the farther it gets from the pivot. This makes my gate very sensitive, and thus the flow is kept much more uniform with the supply than is otherwise practicable.

I have chosen to illustrate my invention as it appears when used in connection with the feed-rolls and hopper of a roller-mill, and, rather for the purpose of showing an alternate construction than otherwise, I have shown a hopper which is applicable to a double mill. Said feed-rolls, however, have nothing to do with my present invention, and might be dis-

pensed with entirely by simply extending the sides of the hoppers down far enough so that the gates would come directly in contact therewith; and it is manifest that the double construction shown is simply a matter of selection, for the reason before stated, and that a single hopper might as well have been shown instead. This invention relates solely to the feed-gate and its operating mechanism, and, as hereinbefore stated, the hopper and feed-roll may be of any form desired.

Having thus fully described my said invention, what I claim as new, and desire to secure by Letters Patent, is—

1. The combination of the feed-hopper, the feed-gate therefor, an arm attached to said feed-gate and extending around to a position inside the hopper, a pressure-board which rests against the inner end of said arm and is supported by a pivot near to or below its lower end, and a spring which exerts its force oppo-

sitely to the pressure of the material upon the pressure-board.

2. The combination of the hopper, the feed-gate A, the pressure-board A², connected to said gate and pivoted near to or below its lower edge, and means for holding said gate downward and said pressure-board forward, substantially as set forth.

3. The combination of the hopper, the gate, the arm, the spring, the pressure-board, and the feed-roll, said several parts being arranged and operating substantially as shown and described, and for the purposes specified.

In witness whereof I have hereunto set my hand and seal, at Indianapolis, Indiana, this 22d day of December, A. D. 1882.

DANIEL W. MARMON. [L. S.]

In presence of—

C. BRADFORD,

E. W. BRADFORD.
